UNITED STATES PATENT OFFICE

153,596

DESIGN FOR A COMBINED CALENDAR AND DESK PAD UNIT

Ernest Frankl, New York, N. Y., assignor to
Stickless Corporation, Bronx, N. Y., a corpora-
tion of New York

Application July 16, 1947, Serial No. 140,324

Term of patent 3½ years

(Cl. D74—5)

To all whom it may concern:

Be it known that I, Ernest Frankl, a citizen
of the United States, residing at New York, in
the county of New York and State of New York,
have invented a new, original, and ornamental
Design for a Combined Calendar and Desk Pad
Unit, of which the following is a specification,
reference being had to the accompanying draw-
ing, forming a part thereof.

The figure is a perspective view of a combined
calendar and desk pad unit, showing my new
design, the printed matter thereon being merely
illustrative of that which will appear from time
to time.

I claim:

The ornamental design for a combined calen-
dar and desk pad unit, as shown and described.
ERNEST FRANKL.
